TRUCK BODY CONSTRUCTION

Maxwell T. Zeigler, Huntington Park, Calif., assignor, by mesne assignments, to Zeigler Packaged Ice Machinery Corporation, Huntington Park, Calif., a corporation of California

Application February 24, 1932, Serial No. 594,913

3 Claims. (Cl. 312—35)

This invention relates to improvements in truck body constructions.

An object of the invention is to provide an improved truck body construction which is primarily designed to transport a series of more or less uniformly sized packages or articles, the construction being such as to facilitate removal of one or more of the packages or articles in making deliveries.

10 It is now being the practice to market ice in packaged form, that is the three hundred pound blocks of ice as delivered from the freezing cans are cut up into small blocks, these usually being in the neighborhood of twenty-five pounds, and wrapped in heavy kraft paper. These packages of ice are sold in vending machines which are regularly serviced from the refrigerating plant and frequently individual deliveries of these packages of ice are made. The improved truck body construction has been primarily designed 15 to handle these packages of ice in transporting them from the refrigerating plant to the vending machines. It may be advantageously employed for this purpose and also for the purpose of making individual deliveries. One object of the invention is to provide a truck body construction in which the interior of the body is divided into a plurality of parallel runways, each runway being designed to receive a row of ice packages or equivalent articles, the design being such 20 as to enable easy loading of the truck and easy unloading. In unloading the truck the design is such as to enable a complete row of packages to be removed from a runway, the packages being removed consecutively, or one package at a time can be removed from the runway in making individual deliveries.

Another object of the invention is to provide a construction of truck body in which each of the packages is so supported that during its movement in the runway abrasion of the wrapping paper wrapper is effectively prevented. When the wrapper is wrapped about ice so that there is a tendency for the wrapper to moisten, the ability 25 of the construction to handle the package without danger of abrading the wrapper is important.

Another object of the invention is to provide a truck body construction having the above mentioned characteristics and which has a suitable cooling means for preserving the interior of the body at a sufficiently low temperature so that the ice will not melt and soak up the paper wrappers, this design being such as to economically use all 30 of the available space within the truck body.

55 Another object of the invention is to provide

a construction in which individual packages of ice are supported in such a manner as to enable free circulation of cold air around each package so that each package is individually cooled or kept cool. If the packages are closely packed 5 together on all sides, only the outer packages of a group will be kept sufficiently cool to prevent or retard melting. By having the packages supported in such a manner that there is a free circulation of cold air around each package, each 10 individual package will be kept at the desired temperature.

With the foregoing and other objects in view, which will be made manifest in the following detailed description, and specifically pointed out 15 in the appended claims, reference is had to the accompanying drawings for an illustrative embodiment of the invention, wherein:

Fig. 1 is a longitudinal vertical section through the truck body embodying the invention. 20

Fig. 2 is a partial view in vertical section taken substantially upon the line 2—2 upon Figure 1.

Fig. 3 is a partial view in vertical section taken substantially upon the line 3—3 upon Figure 2.

Fig. 4 is a view in elevation of the rear end of 25 the truck body construction.

Fig. 5 is a perspective view of one of the shoes employed in the construction.

Referring to the accompanying drawings, wherein similar reference characters designate 30 similar parts throughout, the chassis of the truck may be of any conventional design. The body of the truck mounted on the chassis has a top wall 10, a bottom wall 11, a front wall 12, and side walls 13 and 14. The construction of these 35 walls may be of any preferred design, however, they preferably have an interior metal lining as indicated at 15 and an exterior metal covering as indicated at 16. Between the lining and the covering there is preferably ample insulating material to insulate the interior of the body against the heat of the atmosphere. The rear wall of the truck body is provided by a vertical central jamb 17 and horizontal jambs 18 connecting the vertical central jamb to the side walls 13 and 14. 40

Doors 20 are preferably hinged to the side walls as by hinges 21 and have latches as indicated at 22 which fasten them in closed positions. These doors cooperate with the vertical central jamb and with the horizontal jambs in providing a 45 rear wall for the body. On both sides of the vertical central jamb 17 and within the body there are a series of rows of longitudinal uprights or posts 23. These are preferably metal rods having their lower ends welded or otherwise se- 50

55

cured to longitudinally extending runners or bases formed of strap iron as indicated at 24. Transverse connecting bars 25 connect the uprights and are secured thereto as by welding, these connecting bars being arranged in horizontal alignment with the jambs 18. Longitudinal connecting members 26 and 27 also connect the uprights 23 and extend longitudinally of the body. The interior space on each side of the vertical central jamb 17 is thus divided into a plurality of parallel runways 28. While the longitudinal connecting members 26 near the upper corners of each runway are straight and flat, the longitudinal connecting members 27 which are located near the lower corners of each runway are angular in cross section, providing rails which extend along the runways serving to guide the articles or packages placed therein. Channels 30 are mounted on the transverse connecting members 25 between the rails formed by the angular connecting members 27. In each runway at its forward end there is a shoe, as shown in Figure 5, having a bottom 31 and a forward upright wall 32. The side edges of the bottom are bent downwardly to engage the horizontal flanges of the angular connecting members 27. A towing member in the form of a flexible leather strap 33 is secured to the under side of the bottom of the shoe and preferably at regular intervals along the strap sections of metallic belt lacing are secured, such as those indicated at 34. The leather strap and the rails are preferably paraffined, the paraffin being employed as a lubricant facilitating the sliding of the shoe on the rails and the movement of the strap 33 in the channels under the low temperature normally maintained within the body. The packages or articles to be transported, such as for example the packages of ice illustrated, are arranged in rows within their respective runways. The foremost package of each row is positioned on the shoe which, when the truck is fully loaded, is at the forward end of its runway. The towing members or straps 33 fit within the channels beneath each row.

As clearly shown upon the drawings, the straps are of sufficient thickness so as to support the bottoms of the packages of ice above the rails. Consequently as the towing members or straps 33 are pulled rearwardly, the packages are merely carried by the straps which act as conveyor belts. The clearance between the packages and the longitudinal connecting members is such that ordinarily the packages merely rest upon the straps without engaging the longitudinal connecting members which define the sides of the runways. Consequently during the movement of the packages there is little danger of abrasion of the paper wrappers due to the sliding engagement with parts of the runway. Under certain conditions, however, the truck body may be on an incline so that the packages have a tendency to lean against the longitudinal members. However, under these abnormal conditions the abrasion on the paper wrappers is very slight.

In order to maintain the desired low temperature within the truck body a cooling tank 35 is disposed centrally of the truck body behind the vertical central jamb 17. This cooling tank is preferably of corrugated sheet metal for purposes of strength and is designed to contain cold brine. An inlet and an outlet for the cooling tank are indicated at 36 and 37 respectively, these having valves 38 and 39. Inlet 36 has a pipe connection to the lower forward corner of

the tank and outlet 37 has a pipe connection with the upper rear corner of the tank. In this manner cold brine can be circulated through the cooling tank when the truck is being loaded at the refrigerating plant so that when the truck is completely loaded the tank 35 will be filled with very cold brine. This brine is delivered through hoses indicated at 40 and taken out through a hose 41. By having the circulation take place from the lower forward corner to the upper rear corner, the tank is effectively purged of any air which it may contain. Due to the low temperature, moisture collects on the tank in the course of time and at intervals it becomes necessary to defrost this tank. During this defrosting the frost melts and the water collects on the bottom of the body. As the bottom slopes forwardly, this water will flow to the forward end of the body from which it can pass through an outlet pipe 42. This outlet pipe has two reverse bends forming a water trap as indicated at 43 so that, although the water can escape from the truck body as it collects, warm air cannot enter the body through the outlet pipe 42.

Suitable cover flaps, preferably in the form of heavy canvas flaps, indicated at 44, are secured to the inner sides of the horizontal jambs 18. These cover flaps are suspended over the rear ends of the runways 28, there being one cover flap for each individual runway.

At the refrigerating plant it is customary to handle the packages of ice on conveyors and by this arrangement the packages can be transmitted directly into the runways from the conveyors. The foremost package is positioned on the shoe and as additional packages in any one runway are fed into the runway the shoe is moved forwardly. When the runways are completely filled the cover flaps 44 are allowed to hang down over their rear ends and the doors are closed. In servicing a vending machine a door can be opened, each door being shown as opening three runways. The cover flap of one runway can be lifted and the packages consecutively removed from it. These can be removed by pulling the shoe rearwardly by the towing member 33. While one runway is being exhausted, the cover flaps of the remaining two exposed runways are allowed to hang down to preserve the low temperature as much as possible within the truck body. While the cover flap of the mentioned runway is being lifted and a package is being withdrawn, the package effectively blocks the entrance to its runway so that the remaining cover flaps covering the remaining runways cooperate with the package in the entrance to the runway being exhausted in forming a barrier preventing ingress of warm air even though the door is opened. Whenever the package is removed from its entrance to the runway, the cover flap immediately falls back into its suspended position to cover the entrance to the runway and prevent this ingress of warm air. The runways can be consecutively emptied in servicing the vending machine and in the event that the truck is used for making individual deliveries the packages can be removed individually.

By the improved construction it will be appreciated that the packages of ice can be conveniently handled and transported. The construction is such as to maintain the desired low temperature within the truck body, thus keeping the individual blocks of ice from melting. The operator never has occasion to enter the truck but may remove the entire contents from the rear. The tail gate on

which he may stand in emptying or loading the truck is indicated at 46 and in place of this a foldable step may be employed if desired.

The rows of packages are held in spaced relation to each other to enable a free circulation of cold air throughout the interior of the truck body so that each package is individually cooled by the cool air circulating from the brine tank. The packages are supported upon the belts or straps 10 33, these straps constituting the primary supports for the packages and, being relatively narrow as compared with the size of the package, they do not interfere with this circulation of cold air. Furthermore as the packages do not slide on the straps but are carried by them danger of 15 wearing through or tearing the wrappers is avoided.

While loading of the truck is taking place, the 20 brine can be circulated through the brine tank by attachment of hoses 40 and 41, these leading from the source of cold brine in the refrigerating plant. In use of the truck it is customary to attach these hoses to the brine tank at the start of the loading operation. At night it is customary 25 to load the truck and allow brine circulation to take place all night to reduce the interior temperature to the lowest point possible. The following morning the truck driver can immediately proceed with his truck fully loaded and in a cool 30 condition on merely detaching the hoses.

I find that the use of the truck is such as to enable dispensing with the help of one man's services entirely in that the driver can easily load and unload without the assistance of a helper.

35 From time to time it may be necessary to replace the insulation or to replace the lining for the truck. This can be easily accomplished by taking out the rear horizontal jambs and leaving the doors open. The frames formed by the posts 40 or uprights and the connecting members can each be withdrawn as an entirety through the openings on both sides of the vertical central jamb. Thereafter the lining can be detached from the insulation and removed in sections, that 45 is the side wall sections of the lining can be detached from the insulation, tilted slightly, and

removed. The same is true of the top and front wall of the lining. The insulation can be replaced and the lining either replaced or reinstalled, after which the frames can be reinserted in the truck as complete units and the horizontal jambs replaced.

5 Various changes may be made in the details of construction without departing from the spirit or scope of the invention as defined by the appended claims.

10 I claim:

1. A truck body construction having top, bottom, and side walls, means dividing the interior space into a plurality of runways, a channel in each runway extending substantially the complete length thereof, and a flexible tow strap 15 slidable in each channel extending substantially the complete length thereof and projecting above the sides of the channel so that articles placed in the runways will be supported upon the tow straps 20 above the sides of the channels.

2. A truck body construction having top, bottom, and side walls, means dividing the interior space into a plurality of runways, a channel in each runway extending substantially the complete length thereof, a flexible tow strap 25 slidable in each channel extending substantially the complete length thereof and projecting above the sides of the channel so that articles placed in the runways will be supported upon the tow straps 30 above the sides of the channels, and a shoe at one end of the tow strap.

3. A truck body construction having top, bottom, and side walls, means dividing the interior space into a plurality of runways, a channel in 35 each runway extending substantially the complete length thereof, and a flexible tow strap slid- able in each channel extending substantially the complete length thereof and projecting above the sides of the channel so that articles placed in 40 the runways will be supported upon the tow straps above the sides of the channels, guides at the sides of the channels, and a shoe secured to one end of each tow strap having portions engageable with the guides.

45 MAXWELL T. ZEIGLER.
